(57) **CLAIM**

The ornamental design for a sheet pile connector, as shown and described.

DESCRIPTION

FIG. 1 illustrates a front perspective view of my design; and, FIG. 2 illustrates a side view of the design shown in FIG. 1. The appearance of any portion of the article between the break lines shown in FIG. 1 forms no part of the claimed design.

1 Claim, 2 Drawing Sheets

FIG. 1

FIG. 2
